UNITED STATES PATENT OFFICE

EDWARD D. DAVIS AND GUSTAV A. CARLSON, OF CHICAGO, ILLINOIS, ASSIGNEES TO THE BOYE NEEDLE COMPANY, OF CHICAGO, ILLINOIS, A CORPORATION OF ILLINOIS

DISPLAY SUPPORT

Application filed March 19, 1930. Serial No. 437,203.

This invention relates to display boards for articles to be vended and is particularly useful in connection with the vending of small articles which are sold in groups or bunches, such as, for example, hair pins.

One of the objects of the invention is to provide simple and inexpensive means for supporting in an attractive way articles, such as hair pins, in bunches, the articles being readily removable from the display board without affecting or breaking their bond or sheath. A further object is to provide means whereby a bundle of articles may be supported firmly on a display board and latching or locking means which will prevent removal from the board even during rough usage. Other objects and advantages will appear as the specification proceeds.

This invention is fully described in the following specification and shown in the accompanying drawings, in which

Figure 1 is a front view in elevation of a display board embodying our invention; Fig. 2 is a rear view of the same; Fig. 3 is a side view in elevation of a single hair pin which may be conveniently supported within our improved display support; Fig. 4 is a sectional view, the section being taken as indicated at line 4 of Fig. 1; Fig. 5 is a front view of a modified form of display support embodying our invention; and Fig. 6 is a rear view of the modified form of device shown in Fig. 5.

In the illustrations given 1 represents a display board, which may be of any desirable and attractive shape and formed of any suitable material such as, for example, cardboard. Board 1 is preferably provided with a series of longitudinal openings 2. These openings may be formed by slitting the cardboard, or by cutting out strips or sections of the cardboard of any suitable shape or size.

The articles to be displayed, such as, for example, hair pins, are preferably secured in bunches or bundles by means of a sheath, the sheath being preferably of a shape and size which will enable it to be inserted laterally through the openings 2 in the display board so that a portion will extend through the opening. Preferably the sheath is formed

of some rigid material which will enable it to be pressed firmly against the side walls of an opening 2, and fitted within the opening sufficiently tight to secure the sheath firmly within the board. In the illustration given, 55 the sheath is represented as a thin washer-like member 3. The member 3 has wide flat sides 4 which are adapted to engage the side walls of opening or slit 2 and to be thus secured firmly in position. Preferably the opening 2 is of such length that the member 3 cannot pass completely therethrough. As shown more clearly in Fig. 4, only a portion of the member 3 extends through and to the rear of the display board 1. 65

In the operation of the device, a suitable bundle of articles, such as hair pins, are passed through a pair of retaining rings so as to be confined therein. Preferably in securing the hair pins, the rings 3 are brought into 70 close relation with the waves at the intermediate portions of the hair pins so as to secure them against longitudinal movement. The members 3 are then inserted through openings 2 to support the bundle upon the 75 board 1. To latch the members 3 in position upon the board a latch bar 5 is inserted through the opening 6 provided by the portion of the member 4 which extends through the board 1. The latching bar 5 extends 80 along the rear side of the board 1 and is held in engagement with the washer or sheath 3 by the pressure exerted by the bundle of hairpins upon the front face of the board. To secure the sheath 3 more rigidly in position, 85 it is preferred to employ as latch bar 5 a spring wire which will tend to exert pressure upon the rear side of board 1. In the vending of hairpins, a single hairpin has been found to be preferably applicable for use as 90 a latch bar, in that it possesses the quality of resilience. Another advantage is that the purchaser, upon turning the display board about, can examine, as a separate specimen 95 of the hairpins confined in the bundle on the front side of the board, the hairpin which is used as a latch bar.

When hairpins of various lengths are displayed upon the board 1, it is preferred to employ as latching bars on the rear side, hair- 100

pins which correspond in length and other characteristics to the bundle of hairpins confined within the same washers on the opposite side of the board. With this arrangement, 5 the display board serves not only as a display of the hairpins in bulk or in bundles but also as a display of single hairpins.

In removing the hairpins from the display board, the pins may be withdrawn singly through the washers 3, or the latching bars 5 may be withdrawn at the rear side of the board, thus permitting removal of the bundles. Individual hairpins may be readily withdrawn, as desired, from the bundles 15 confined within the washers.

The display board 1 serves not only as an attractive means of displaying the hairpins prior to sale but also serves as a package in which the pins may be conveniently preserved 20 by the customer after the purchase.

In the modification shown in Figures 5 and 6, a single sheath or washer 3 is employed. Preferably, the washer is placed about the waved or corrugated portions of the hairpins so as to confine them in a compact bundle. 25

The foregoing detailed description has been given for clearness of understanding only, and no unnecessary limitations should 30 be understood therefrom, but the appended claims should be construed as broadly as permissible, in view of the prior art.

We claim:

1. A display support comprising, a display 35 board provided with slotted openings, washers confining a plurality of hair pins in a bundle, said washers having a portion adapted to extend through said openings and spring latch bars extending through said 40 washers on the rear side of said board, said latch bars comprising hairpins.

2. A display board comprising, a board provided with openings, rigid ring members adapted to retain a plurality of hair pins 45 within a bundle, said rings being adapted to extend in part through said openings, and single hair pins adapted to extend through said rings on the rear side of said board, each of said single hair pins on the rear side of 50 said board corresponding to the hair pins confined with it within the same ring.

3. In combination, a display board provided with openings, washers confining articles in bundles, said washers being adapted 55 to extend through said openings, and latching means extending along the rear side of said display board and engaging said washers, said articles being removable from said board still confined in bundles by said washers, upon the release of said latching means. 60

4. A display support comprising a display board equipped with an opening, a washer member confining a plurality of articles in a bundle, said washer member having a portion adapted to extend through said open- 65

ing, and latching means adapted to extend through said washer member on the rear side of said board, said latching means comprising a single article corresponding to the articles confined by the washer on the opposite side of the board. 70

5. A display board comprising, a board provided with openings, rigid washers adapted to confine a plurality of articles within a bundle, said washers being adapted to extend in part through said openings, and single articles extending through said washers on the rear side of said board, each of said single articles on the rear side of said board corresponding to the articles confined with it within the same washer. 75 80

6. In combination, a display board provided with an opening, a retaining band confining articles in a bundle, said band being adapted to extend through said opening, and releasable latching means extending along the rear side of said display board and engaging said band, said articles being removable from said board still confined in a bundle by said band, upon the release of said 90 latching means. 85 90
